UNITED STATES PATENT OFFICE.

JOSEF BENEŠ, OF PRAGUE, CZECHOSLOVAKIA.

DESIGN FOR A COMBINED POCKET MIRROR AND POCKET LAMP.

Application filed March 27, 1924. Serial No. 9,074. Term of patent 3½ years.

To all whom it may concern:

Be it known that I, JOSEF BENEŠ, a citizen of the Republic of Czechoslovakia, residing at Prague, in the State of Czechoslovakia, and whose post-office address is Perlova 8, Prague I, have invented a new, original, and ornamental Design for a Combined Pocket Mirror and Pocket Lamp, of which the following is a specification, reference being had to the accompanying drawing, forming part thereof.

The figure in the drawing is a perspective view of the article showing my new design.

I claim:

The ornamental design for a combined pocket mirror and pocket lamp as shown.

In testimony whereof affix the signature in presence of two witnesses.

JOSEF BENEŠ.

Witnesses:

DR. MÜLLER,
S. COZKOVÁ.
